(57) **CLAIM**

The ornamental design for a glass cabinet, as shown and described.

DESCRIPTION

FIG. 1 is a front, left, top perspective view of the first embodiment of a glass cabinet, showing my new design; FIG. 2 is a rear, right, bottom perspective view thereof; FIG. 3 is a front elevational view thereof; FIG. 4 is a rear elevational view thereof; FIG. 5 is a left side view thereof; FIG. 6 is a right side view thereof; FIG. 7 is an enlarged top plan view thereof; FIG. 8 is an enlarged bottom plan view thereof; FIG. 9 is an enlarged view of detail 9 in FIG. 1; FIG. 10 is an enlarged view of detail 10 in FIG. 1; FIG. 11 is an enlarged view of detail 11 in FIG. 1; FIG. 12 is an enlarged view of detail 12 in FIG. 2; FIG. 13 is an enlarged view of detail 13 in FIG. 3; FIG. 14 is an enlarged view of detail 14 in FIG. 4; FIG. 15 is a front, left, top perspective view of the second embodiment of a glass cabinet; FIG. 16 is a rear, right, bottom perspective view thereof; FIG. 17 is a front elevational view thereof; FIG. 18 is a rear elevational view thereof; FIG. 19 is a left side view thereof; FIG. 20 is a right side view thereof; FIG. 21 is an enlarged top plan view thereof; FIG. 22 is an enlarged bottom plan view thereof; FIG. 23 is an enlarged view of detail 23 in FIG. 15; FIG. 24 is an enlarged view of detail 24 in FIG. 15; FIG. 25 is an enlarged view of detail 25 in FIG. 15; FIG. 26 is an enlarged view of detail 26 in FIG. 15; FIG. 27 is an enlarged view of detail 27 in FIG. 15; FIG. 28 is an enlarged view of detail 28 in FIG. 16; FIG. 29 is an enlarged view of detail 29 in FIG. 17; and, FIG. 30 is an enlarged view of detail 30 in FIG. 18.

The dashed broken lines in the figures are for the purposes of illustrating portions of the glass cabinet and form no part of the claimed design.

The dash-dot-dash broken lines are for notating enlarged views and form no part of the claimed design.
